(57) **CLAIM**

The ornamental design for a hat, as shown and described.

DESCRIPTION

FIG. 1 is a rear perspective view of a first hat incorporating our new design;

FIG. 2 is a rear elevation view thereof;

FIG. 3 is a front elevation view thereof;

FIG. 4 is a right side elevation view thereof, wherein the left side elevation view is a mirror image thereto;

FIG. 5 is a top plan view thereof; and

FIG. 6 is a bottom plan view thereof.

FIG. 7 is a rear perspective view of a second hat incorporating our new design;

FIG. 8 is a rear elevation view thereof;

FIG. 9 is a front elevation view thereof;

FIG. 10 is a right side elevation view thereof, wherein the left side elevation view is a mirror image thereto;

FIG. 11 is a top plan view thereof; and,

FIG. 12 is a bottom plan view thereof.

The features of the article shown in broken lines in the drawing figures illustrate environmental subject matter and form no part of the claimed design.

1 Claim, 6 Drawing Sheets
